UNITED STATES PATENT OFFICE

2,153,368

LAMP SOCKET

Frank C. De Reamer, Bridgeport, Conn., assignor to General Electric Company, a corporation of New York

Application March 3, 1937, Serial No. 128,804

7 Claims. (Cl. 173—328)

The present invention relates to lamp sockets or holders, and especially to lamp sockets or holders for long cylindrical lamps having a contact ferrule at each end.

One object of my invention is to provide a lamp socket for a lamp of this type which, while being efficient in operation, comprises few parts and is capable of being manufactured at low cost.

A further object of my invention is to provide a lamp socket which is attractive in appearance and in which all exposed parts are of metal so that the socket may be given a uniform finish to match with the fixture with which the socket is used.

For a consideration of what I believe to be novel and my invention, attention is directed to the following specification and the claims appended thereto.

In the drawing, Fig. 1 is a perspective view of a lamp of the type referred to supported in a lamp fixture utilizing sockets or holders embodying my invention; Fig. 2 is an exploded view showing the parts of the socket; Fig. 3 is a perspective view of an adapter which is attached to an end of the lamp for connecting the ferrule to the socket; Fig. 4 is an enlarged sectional view of a socket with the end of a lamp mounted therein, and Fig. 5 is a sectional view taken on lines 5—5, Fig. 4.

Referring to Fig. 1, 6 indicates a lamp of the referred to type, the ends of which are supported in lamp sockets 7, the lamp sockets in turn being supported by a tube 8 attached to a supporting base 9. The electric wires for the lamp extend through the tube 8, one wire going to each socket, as is well understood, and supplying current to the filament of the lamp. This lamp fixture is shown only by way of example and to illustrate generally the way in which the sockets 7 are used.

Referring to Figs. 2 to 5 inclusive, the lamp socket comprises a base 10 of suitable insulating material provided at one end with a radially extending recess having an outer portion 11 with straight parallel walls which form a guide and an undercut inner portion 12 having sloping side walls as shown particularly in Fig. 5. Projecting forwardly from the rear wall 13 of the recess and formed integral therewith is a forwardly projecting tongue 14 which is spaced from the side walls and bottom wall of the inner portion 12 of the recess as shown particularly in Fig. 5, forming therewith a triangular shaped space. Located in the triangular shaped space is a contact clip comprising a base portion 15 having a forwardly projecting integral collar 16 which forms a thickened part in which is a tapped hole for a binding screw 17, and a pair of spring contact arms

18 which form a U-shaped connector. The lower side of tongue 14 has a groove 19 to accommodate the collar 16 and the upper surface is curved as indicated at 20 to provide a seat for a contact pin. In assembling the contact clip in the base, it is slid into the triangular shaped groove from the right hand end, as shown in Fig. 2, after which the binding screw 17 is threaded into the tapped hole in the base portion 15. The screw then serves to hold the contact clip in the groove by means of the shoulder 17a adjacent the screw head, as shown in Fig. 4.

In the lower rear portion of base 10 is a suitable recess 21 through which the electric wire extends to the binding screw 17. Also, the rear 15 portion is hollowed out, as shown at 21a, to lighten the structure and decrease the amount of material required for the base. On opposite sides of base 10 are passages 22 in which are located screws 23 which serve to fasten the base to a metal cap 24.

The metal cap 24 comprises a threaded nipple 25 and a shell 26 provided at a plurality of spaced points with indentations 27 for engagement with a screw thread. Attached to the nipple inside the cap are bracket arms 28 having tapped openings in their ends into which the screws 23 thread to attach the base 10 firmly to the cap. The base is of smaller diameter than the cap as is seen particularly in Fig. 4 so as to provide an annular 30 space between the base and the cap. The cap is of slightly greater diameter than the lamp. Surrounding base 10 is a cylindrical metal sleeve 29 which is threaded at its inner end and is provided with a liner 30 of insulating material. The 35 threads on sleeve 29 thread into shell 26 of the cap as shown in Fig. 4, the indentation 27 in the cap serving as cooperating screw threads.

The ends of the lamp are provided with metal ferrules 31 as shown in Fig. 4 provided with central undercut depressions 32. For connecting the ferrule to the clip of the holder, I provide an adapter as shown in Fig. 3, the same comprising a disk 33 having on one side a headed spring button 34 adapted to snap into the depression 32 and on the other side a contact pin 35 adapted to engage between the clip arms 18. The adapter may to advantage be made from two stampings fastened together by turning the outer edge of one over the edge of the other, as is shown in the 50 sectional view in Fig. 4.

In the use of the invention, the lamp sockets are attached to a supporting means such as the tube 8 by means of the threaded nipples 25, the sockets being spaced to receive a lamp between 55

them. The metal sleeves 29 with liners 30 therein are screwed out of the caps 24 and slipped over the body of the lamp, and the electric conductors are connected to the binding screws 17. The 5 lamp, with adapters attached to each end, is then mounted in the lamp sockets by passing the pins 35 of the adapters through the straight portions 11 of the recesses into engagement with the seats 20, the pins 35 being sprung into position between 10 the contact arms 18. The sleeves 29 with the liners 30 therein are then slid over the base 10 and threaded into the caps 24. This completes 15 the assembly. The lamp can be removed easily at any time by unscrewing the sleeves 29 and slipping them back over the body of the lamp and then lifting the lamp out of the holders.

When a lamp is in position, it will be noted that only metal parts of the holders or sockets 7 are exposed. This enables the socket to be 20 finished exteriorly as desired so it may be made to match the fixture with which it is used. At the same time, the socket is simple in structure, comprising few parts and is capable of being manufactured at low cost.

25 Also, when the lamp is in position, as shown in Fig. 4, and the sleeve is attached to the cap, it will be seen that the sleeve at its inner end surrounds and engages the end of the lamp and spans the space between the lamp and the cap, 30 thus entirely enclosing the base 10.

What I claim as new and desire to secure by Letters Patent of the United States is:

1. In a lamp socket, the combination of a cap, a longitudinal base of less width than the cap 35 and being attached thereto, said base having a laterally opening recess, contact means in said recess for receiving a contact element of a lamp, and a sleeve which surrounds the base and being of a width such that it will slip over the body of 40 the lamp as said lamp is moved laterally of said base to bring the lamp contact element into engagement with said contact means and thereafter being movable axially of the lamp to engage said cap and enclose said base.

45 2. In a lamp socket, the combination of a longitudinal base having a laterally opening recess at one end, contact means in said recess for receiving a contact element of a lamp with the lamp adjacent said end of the base, a cap attached to the other end of the base having a flange which surrounds such end, and a cylindrical sleeve of a diameter greater than that of the lamp to be used with the socket which surrounds 50 and encloses the base extends between the cap

and lamp and is detachably connected to said cap.

3. The combination with a cylindrical lamp having a projecting contact pin at its end of a holder comprising a base having a laterally opening recess at one end, a spring contact in the recess to engage and hold the contact pin as said lamp is moved laterally into engagement with said base, a cap attached to the other end of the base, and a sleeve which surrounds the base, 10 spans the space between the end of the lamp and the cap and is detachably connected to the cap.

4. In a lamp socket, the combination of a base having a laterally opening recess at one end, a tongue in the recess spaced from the bottom and 15 side walls thereof to form a triangular shaped passage, a contact clip having a base portion in the space between the tongue and the bottom wall of the recess and spring arms projecting from the base to points beyond the tongue, the upper 20 surface of the tongue forming a seat for a contact pin held between said spring arms, and a binding screw in the base portion of the contact clip and cooperating with said bottom wall to hold the contact clip in position.

25 5. An adapter for a lamp of the type having a metallic ferrule at each end provided with a depression comprising a disk having spring means on one side for engaging a depression in a lamp ferrule and a projecting contact pin on the other 30 side said spring means and contact pin being in axial alignment.

6. An adapter for a lamp of the type having a metallic ferrule at each end provided with a depression comprising two metallic circular plates 35 fastened together flatwise, one plate having spring means projecting therefrom for attaching it to a lamp ferrule and the other plate having a contact pin projecting therefrom.

7. In a lamp socket, a base having a laterally 40 opening recess at one end, contact means in said recess, a disk having a projecting pin on one side engaging said contact means and having spring means on the other side adapted to engage a lamp ferrule whereby the lamp may be moved 45 laterally on said base to engage and disengage said pin with said contact means, a cap attached to the other end of the base having a flange surrounding the end and a sleeve detachably connected to the cap and surrounding the base, said 50 sleeve being of a diameter substantially the same as that of the lamp.

FRANK C. DE REAMER.
